BATTERY CHARGER

Robert J. Debrey, Edina, Minn., assignor to Magnetic
Controls Company, Minneapolis, Minn.

Filed Apr. 15, 1974, Ser. No. 461,154

Term of patent 14 years

Int. Cl. D13—02

U.S. Cl. D26—15 B

FIG. 2

FIG. 1

FIG. 3

FIG. 4

FIG. 5

FIG. 1 is a front elevation of a battery charger showing my new design;

FIG. 2 is a top plan view of the battery charger of FIG. 1;

FIG. 3 is an elevational side view of the battery charger as viewed from the right hand side of FIG. 1, the left hand side being substantially a mirror image thereof;

FIG. 4 is an elevational view of the back side of the battery charger or the side opposite to that shown in FIG. 1; and

FIG. 5 is a bottom plan view of the battery charger. I claim:

The ornamental design for a battery charger, as shown and described.
